UNITED STATES PATENT OFFICE.

EDWARD J. MOORE, OF CLEVELAND, OHIO, ASSIGNOR OF ONE-HALF TO THE SHERWIN-WILLIAMS COMPANY, OF CLEVELAND, OHIO, A CORPORATION OF OHIO.

BAIL-EAR-SOLDERING MACHINE.

SPECIFICATION forming part of Letters Patent No. 764,536, dated July 5, 1904.

Application filed June 18, 1903. Serial No. 161,977. (No model.)

To all whom it may concern:

Be it known that I, EDWARD J. MOORE, a citizen of the United States, and a resident of Cleveland, county of Cuyahoga, and State of Ohio, have invented a new and useful Improvement in Bail - Ear - Soldering Machines, of which the following is a specification, the principle of the invention being herein explained and the best mode in which I have contemplated applying that principle, so as to distinguish it from other inventions.

My invention relates to devices for soldering bail-ears to the sides of pails or cans, its object being to effect such soldering with facility and celerity and in an economical manner.

Said invention consists of means hereinafter fully described, and particularly set forth in the claims.

The annexed drawings and the following description set forth in detail certain means embodying the invention, such disclosed means constituting but one of various mechanical forms in which the principle of the invention may be used.

In said annexed drawings, Figure I represents a side elevation of the mechanism of a bail-ear-soldering device embodying my invention detached from its supporting - base. Fig. II represents a longitudinal central section of a portion of the device on the lines 2 2 of Figs. III, IV, and VII. Fig. III represents a plan view of such mechanism, parts being broken off and shown in dotted lines. Fig. IV represents a horizontal section taken on the plane indicated by the lines 4 4, Figs. I, II, V, VI, and VII, and plan view of the said mechanism with parts removed. Fig. V represents an end elevation. Figs. VI and VII represent vertical transverse sectional views taken upon the planes indicated by lines 6 6 and 7 7, Figs. I and III. Fig. VIII represents a transverse sectional view of a portion of a can or pail, showing a bail attached thereto and partly in section. Fig. IX represents an axial section of a portion of such can or pail with the attached bail in section. Fig. X represents a plan view of a bail-ear with a por-

tion of a bail attached thereto. Fig. XI represents a view similar to Fig. II, but on an enlarged scale and with some parts removed and representing the relative position of the parts when the forward end of the lever B is at its lowest position and after the cross-head D' has been pulled farthest to the right and released. Fig. XII represents a view similar to Figs. III and IV, but on the same scale and with the same relative positions as in Fig. XI and in general of the same parts as in said Fig. XI. Fig. XIII represents a view similar to Fig. VI, but on the same scale and in general of the same parts as those of Fig. XI.

Upon the middle portion of a base-plate A is bolted an upright frame A', extending transversely across the plate A, as shown in Fig. VII. Upon the top and in the middle of said frame are supporting-ears *aa*, which serve to guide a lever B, oscillatory in vertical planes and mounted upon a pivot-bolt *a'*, as shown. At each side of said ears *aa* are secured, by means of suitable bolts, two forwardly-projecting plates C C, whose forward portions *cc* are inclined downwardly from the sides of the machine toward its middle, as shown in Figs. V and VI. Lying upon and pivoted so as to be capable of oscillation upon and in a plane parallel with the inclined surface of each of said plates C C is a plate C', each of the latter having secured thereto a small reservoir C² for containing flux, such as muriatic acid or sal-ammoniac. From each such reservoir there extends in a forward direction a curved feeding-tube *c'*, provided with a cock *c'* and with a small piece of sponge *c'* in its extremity, such cock and sponge regulating the discharge of flux from the tube end.

Upon the under side of frame A' is bolted a hanger *a'*, in which is rigidly secured a forwardly-extending guiding-bar D, upon which is mounted a sliding cross-head D'. This cross-head is normally urged forward by means of a spring *a''*, secured to the base-plate, as shown in Fig. II. To this cross-head and upon opposite sides thereof are pivotally secured the inner ends of two links *d d*, whose upper ends are pivotally secured to the two

oscillatory plates C' C' and in a manner such that reciprocation of the cross-head D' will effect the oscillation of the plates C' C', the reservoirs C² C², and the feeding-tubes c' c'.

5 The oscillatory lever B is provided with a downwardly-projecting arm b, which is provided with a pawl b', actuated upwardly by means of a spring b² to engage a notch d', formed upon the lower surface of the cross-head D', such engagement being effected when the forward end of the lever B is in its extreme upward position. The rear end of said lever B is provided with a counterweight B', which normally holds the front end thereof 10 in its elevated position, as shown in Fig. I. Such front end is provided with a combustion-chamber B² for heating a soldering-iron B³. Said soldering-iron is cup-shaped to receive and embrace a bail-ear, as will be further described. Hung from the extreme rear end of said lever is a connecting-rod b³, which is provided with a treadle (not shown) whereby such rear end may be elevated to depress the forward end by foot-pressure, as will be 15 further described. Upon the rear end of the base-plate are mounted two reels E, upon which are wound coils or strips of soldering-wire c. Upon each side of the frame A' are mounted two grooved feeding-rolls F F, 20 adapted to receive the said wire and when turned to feed the same forward. These rolls are provided with gears f f, meshing with each other, so as to effect the simultaneous rotation of the two rolls. Rotation of the 25 lower of the two rolls and gears is effected by means of a shaft f', upon which such lower rolls and gears are mounted, the shaft being rotated by means of a gravity-operated pawl f', mounted so as to be capable of oscillation, 30 Fig. II, and engaging during its rearward stroke a ratchet-wheel F', secured to the shaft. This pawl is mounted upon an oscillatory arm f³, hung from the shaft, and is connected with the arm b by means of a link b⁴. Said 35 link may be connected with said arm at various points by means of holes f⁴ formed therein, as shown and as will be readily understood, so as to vary the throw of the arm, and hence the amount of feed effected by the 40 feeding-rolls.

In front of each pair of feeding-rolls and loosely mounted upon the frame A', by means of enlarged holes g for receiving supporting-screws a⁴, as shown in Fig. I, is a plate G, 45 which may be oscillated in vertical planes, the screws a⁴ having their heads left a distance from the frame sufficient to permit such oscillation to take place. Fixed to each said plate G is an inwardly-extending arm g', 50 Fig. VI, whose inner ends lie in the rear end of the path of the arm b and which are normally held in a forward position by means of springs a⁵ a⁵, secured to the frame A'. In each such plate is formed an aperture g² 55 opposite the space between the two rolls F F,

into which is screwed a pipe G' for guiding the solder strip from the rolls to the desired point of application on the can or pail and curved inwardly, as shown in Fig. III.

Upon the front portion of the frame A is 70 secured a rest or cradle H for receiving and holding the can or pail in a position such as to bring the surface to which the ear is to be soldered in the path of the soldering-iron B³ and preferably made of sheet metal bent to 75 form a base portion and a concave top portion, as shown. This rest is adjustable toward and from the base-plate, so as to accommodate cans of various diameters to effect their required position relatively to said soldering-iron. Such adjustment may be effected in 80 various ways, an adjustable rod h, secured by a set-screw h¹, being provided for that purpose in the machine illustrated. The rest is secured to a plate h², secured to or formed integral with the top of rod h by means of thumb-screws h³ and bolts h⁴ passing through a transverse slot h⁵ in the base portion of the rest, as shown in Figs. IV and V in dotted lines, whereby the rest may be adjusted transversely. 85

From the above-described construction it will be seen that the elevation of the rear end of the lever B effects a downward and rearward movement of the arm b. This arm by 90 reason of its connection with the cross-head D' through pawl b' effects the rearward reciprocatory stroke of same, such stroke being opposed by the spring a³. Simultaneously with such reciprocation the oscillation of supporting-plates C', and hence the reservoirs C², 95 is begun, the extremities of the feeding-tubes c' being moved inwardly and downwardly toward each other until they approach within a short distance of each other, their paths being indicated by dotted lines, Fig. V. The rest H is so adjusted that the sponges in the ends of said tubes will contact a portion of the can-body in that position where it is required that the bail-ear shall be secured, as 100 indicated in said figure, and apply a quantity of flux thereto. The parts are also so arranged that such contact shall take place prior to the time the cross-head reaches its extreme rearward limit of travel. The cross-head having retreated rearwardly some distance by the 105 time such explained application of flux takes place, the downward movement of the arm b carries the pawl b' downwardly, so as to disengage the notch d' immediately thereafter, the spring a³ thereupon being allowed to return the cross-head to its forward position, and so withdraw the ends of the tubes from the vicinity of the bail-ear. Immediately 110 thereafter the arm b strikes the arms g' on the plates G, and its continued rearward movement institutes the oscillatory stroke of such plates G, which carries the ends of the solder-strip-guiding pipes G' inwardly, so as to bring them into the vicinity of the bail-ear, such 115 120 125 130

action being opposed by the springs a^5 . The occupation of the extreme inward position of these pipe ends is effected simultaneously with the arrival of the soldering-iron upon 5 the surface of the can-body. A strip of solder projecting from such ends will hence be caused to contact such iron, be melted, and so permitted to flow to the surfaces in contact with the lower end of said iron. Such described action during the downward movement of the soldering-iron is further accompanied by the operation of the solder-strip-feeding mechanism as a result of the partial rotation of the shaft f' , which, as will appear 10 from the preceding description, rotates the feeding-rolls $F F$ and intermittently advances the solder strip.

Upon reaching the can-surface the soldering-iron receives the bail-ear in the cavity 20 formed for the reception of the latter, so that such iron may contact the required adjacent bail-ear and can-surfaces and allow melted solder thereby to reach the same, such surfaces having been previously supplied with 25 flux. Upon releasing the treadle the soldering-iron retracts, the parts regaining their normal positions, pawl b' reengaging the notch d' in the cross-head.

In order to hold the bail-ears in place prior 30 to soldering and after placing upon the can-surface, a loosely or elastically mounted rod J is attached to the frame A' , which projects forwardly and into the path of the soldering-iron, the latter being provided with a notch 35 b^5 , Fig. V, for receiving it during the act of soldering. This rod is depressed by means of a spring J' acting upon a plunger j , secured to its rear end, which latter is placed in the path of the lever B , as shown. This lever 40 when in its normal illustrated position bears down upon such rear end to elevate the front end of the rod J . Upon the elevation of the rear lever end it will be seen that the rear end of rod J is released, allowing the spring J' to 45 act to depress the front end upon the bail-ear. The combustion-chamber is supplied with gas for heating the soldering-iron by a pipe b^6 , to which is attached a suitable flexible connection (not shown) leading from the gas-supply- 50 ing source. The front end of said rod J is provided with a concave notch j' , Fig. III, adapted to receive a portion of the lateral surface of a bail-ear, the latter when so received being in proper position for soldering.

55 In the operation of soldering bail-ears by means of the above-described device the said ears are placed upon the surface of the can-body or pail after the latter has been placed in the rest H , so as to cause the bail to abut the 60 concave end of rod J , as shown in Figs. IX and X. The treadle is then operated to depress the soldering-iron to inclose the bail-ear, its lower end contacting the required surfaces, such operation having been preceded by 65 the application of flux to the said surfaces and

the application of solder to the iron. The rod J is meanwhile permitted to bear upon and hold the ear in place during such operation. One ear having thus been soldered, the can is turned around so as to bring into position the 70 surface diametrically opposite that to which such ear has been attached and the second ear attached to such diametrically opposite surface. In order to facilitate the proper placing of the can for the application of such second ear, the rest H is provided with a notch h^6 , intersecting the middle of the forward extremity of its upper portion, which receives the ear first secured and then determines the 75 position of the second ear.

80 Other modes of applying the principle of my invention may be employed instead of the one explained, change being made as regards the mechanism herein disclosed, provided the means stated by any one of the following 85 claims or the equivalent of such stated means be employed.

I therefore particularly point out and distinctly claim as my invention—

1. In a bail-ear-soldering machine, the combination of a holder for receiving the article to be operated upon, means for applying flux, means for applying solder, separate means comprising a soldering-iron movable toward and from said holder and means for operating the same, said flux and solder applying means being operated by said soldering-iron-operating means.

2. In a bail-ear-soldering machine, the combination of a holder for receiving the article to be operated upon, an oscillatory arm movable toward and from said holder and means for operating the same, a soldering-iron mounted upon said arm, movable means for applying flux and movable means for applying solder, 95 said flux and solder applying means being operated by said oscillatory arm.

3. In a bail-ear-soldering machine, the combination of a holder for receiving the article to be operated upon, an oscillatory arm movable 100 toward and from said holder, a soldering-iron mounted upon said arm, oscillatory means for applying flux and oscillatory means for applying solder, said flux and solder applying means being connected with and operated by said oscillatory arm.

4. In a bail-ear-soldering machine, the combination of a holder for receiving the article to be operated upon, an oscillatory arm movable toward and from said holder, a soldering-iron 110 mounted upon said arm, oscillatory fluxing means, and oscillatory means for applying solder, said flux and solder applying means being operated by said oscillatory arm and arranged so as to advance and release said fluxing means during the approach of the soldering-iron.

5. In a bail-ear-soldering machine, the combination of a holder for receiving the article to be operated upon, a soldering-iron mounted so 120

as to be movable toward and from said holder, fluxing means movable in a plane intersecting the plane of movement of the soldering-iron and means for actuating said soldering-iron and fluxing means.

6. In a bail-ear-soldering machine, the combination of a holder for receiving the article to be operated upon, a soldering-iron mounted so as to be movable toward and from said holder, fluxing means movable in a plane intersecting the plane of movement of the soldering-iron, and means for actuating the latter, said fluxing means being operated through the medium of said arm.

15. 7. In a bail-ear-soldering machine, the combination of a holder for the article to be operated upon, an oscillatory arm movable toward and from said holder, and carrying a soldering-iron, separate solder-applying means, and means for receiving and retaining a bail-ear in position upon said article, said solder-applying and retaining means being actuated by said oscillatory arm.

25. 8. In a bail-ear-soldering machine, the combination of a holder for the article to be operated upon, an oscillatory arm movable toward and from said holder, and carrying a soldering-iron, separate solder-applying means, means for receiving and retaining a bail-ear 30 in position upon said article, said solder-applying and retaining means being actuated by said oscillatory arm, and means for determining a definite position upon such article with reference to such first-named ear, at which 35 definite position a second ear may be applied.

9. In a bail-ear-soldering machine, the combination of a holder for receiving the article to be operated upon and provided with means for definitely fixing the position of such article, means for receiving and automatically retaining a bail-ear in position upon such article, flux-applying means, solder-applying means, separate means comprising a soldering-iron movable relatively to said holder and 40 means for operating the same, said flux-applying, solder-applying, and retaining means being operated by said soldering-iron-operating means.

45. 10. In a bail-ear-soldering machine, the combination of a holder for receiving the article to be operated upon, means for applying flux, means for applying solder, and means pro-

vided with a soldering-iron movable relatively to said holder, said flux-applying, solder-applying, and soldering means all arranged to move simultaneously in the direction of said article, and further arranged to contact with said article successively.

11. In a bail-ear-soldering machine, the combination of a holder for receiving the article to be operated upon, oscillatory means for applying flux, oscillatory means for applying solder, and means provided with a soldering-iron movable relatively to said holder, said flux-applying, solder-applying, and soldering means all arranged to move simultaneously in the direction of said article, the oscillatory stroke of said flux-applying means being accomplished during the forward stroke of said solder-applying and soldering means.

12. In a bail-ear-soldering machine, the combination of a holder for receiving the article to be operated upon, oscillatory means for applying flux, oscillatory means for applying solder, and an oscillatory arm provided with a soldering-iron, said flux-applying, solder-applying, and soldering means all actuated by said oscillatory arm, all arranged to move simultaneously in the direction of said article, and said flux-applying means contacting with said article prior to the contact of the same by said solder-applying and soldering means.

13. In a bail-ear-soldering machine, the combination of a holder for receiving the article to be operated upon and provided with means for definitely fixing the position of such article, means for receiving and automatically retaining a bail-ear in position upon said article, oscillatory means for applying flux, oscillatory means for applying solder, and an oscillatory arm provided with a soldering-iron, said flux-applying, solder-applying, soldering, and retaining means all actuated by said oscillatory arm, all arranged to move simultaneously in the direction of said article, and said retaining and flux-applying means contacting with said article prior to the contact of the same by said solder-applying and soldering means.

Signed by me this 26th day of May, 1903. 100
EDWARD J. MOORE.
